PROCESS OF MAKING A WELT SHOE WITH WELT-FORMING SOLE

William B. L. Freeman, Brookline, Mass.

Application September 13, 1956, Serial No. 610,050

13 Claims. (Cl. 12—142)

This invention comprises a new and improved process of making welt shoes in which the upper is fitted to a last, pulled over and lasted thereon.

The process of my invention is characterized by the employment of a welt-forming sole in accordance with the following steps, viz. securing to the bottom of a lasted upper a flat sole, hereinafter termed a welt sole, having a partially severed blank in its forepart which defines a flat marginal welt strip, removing the last and attaching the upper to the said welt strip by stitching or cement, then removing the partially severed blank, laying an outsole and stitching it to the welt strip thus provided. If desired, a light flexible filler or cushion may be inserted to replace the removed blank.

In forming a welt as above outlined, certain disadvantages of the conventional Goodyear welt shoe are obviated. Instead of dealing with a loose welt strip that requires a high degree of skill in properly locating and attaching and then requires a welt beating operation preparatory to receiving an outsole, my improved process provides at once from the material of the welt sole a thin, flat, accurately located welt strip and so obviates the costly welt sewing and welt beating operations. On the contrary, the welt strip is economically formed as a stock fitting operation and is properly located in the routine step of laying the midsole that requires no high degree of skill. It will thus be apparent that my novel process may be carried out by regular and conventional steps of shoemaking.

In accordance with my novel process the welt may be formed about the forepart of the shoe only or about the entire periphery of the shoe with or without employing a dutchman in the heel seat. I employ as the welt sole of my process a conventional midsole or forepart slip sole and die out a blank from the center or from the forepart of such shape as to define a flat marginal welt strip. The die out blank may be completely severed and held in place during the shoemaking process by means of tape or staples or stitching, or it may be partially severed and retained in place by unsevered key spots of minimal dimension. The midsole or welt sole may be of any material ordinarily used for such shoe parts as leather, rubber, or any of the synthetic sole materials now available in the open market.

Welt shoes constructed in accordance with my novel process have the advantage of lightness, flexibility and economy of manufacture. By removing the blank from the interior of the midsole, the stiff plywood effect in the shoe bottom is avoided and flexibility greatly increased. The shoe is made lighter because the blank removed from the midsole is replaced by a light flexible cushion of felt, foam rubber, cork or the like. The welt strip is accurately and properly located once for all in correct and predetermined curvature and by this expedient a welt strip may be provided in shoes such as those of the genuine moccasin type where it has been heretofore difficult to attach welting uniformly and efficiently. The presence

2

of the partially severed blank during the step of sewing the upper thereto holds the lasted shoe in its initial lasted position and positively stabilizes and prevents misplacement of the welt along the longitudinal and lateral axes of the shoe. It is also noted that the transverse line of stabilization is preferably at the ball line of the shoe. Thus is produced a shoe which is light, which is flexible, which adds nothing complicated to conventional shoemaking processes, which can be repaired, which has the appearance of a double sole shoe, and is more economical to produce than any type of shoe heretofore known having these valuable characteristics.

The removal and replacement of the blank from the midsole gives the manufacturer the advantage that he may quite properly utilize low grades of midsoles with scars or other defects in the portions because of the fact that many of these defects will be removed with the severed blank. This permits the manufacturer to achieve an important reduction in the cost of his midsoles. Further, because of the fact that the entire unit is preformed and goes through the midsole laying and attaching process as a unit, shoes of uniform or identical appearance may be made because the fixed outer edge of the midsole is used as a guide for subsequent operations. Ordinarily in attempting to attach welts to shoes other than Goodyear welt shoes, many shoes are damaged where the welt runs off from its true location in certain spots. In practising the process of the present invention damage of this sort is entirely obviated. Another advantage is that the welt strip is formed continuously and there is no necessity of splicing to join the ends of the welt and no possibility of opening occurring at the splice which would, of course, result in rejects.

The shoe produced as above outlined, while having a bottom of substantial thickness, is substantially as light and more flexible than a single sole shoe. It provides comfort to the wearer not only by its increased lightness and flexibility, but also on account of the cushion characteristics imparted to it by the filler. When it becomes necessary the shoe may be repaired in the usual manner with all the convenience of a welt shoe.

These and other advantages of the invention will be best understood and appreciated from the following description of a preferred manner of carrying out the process illustrated in the accompanying drawings in which:

Fig. 1 is a view in perspective of a lasted upper of the moccasin type;

Fig. 2 is a similar view showing the midsole in position on the shoe bottom;

Fig. 3 is a similar view suggesting the replacement of the partially severed blank by a filler cushion;

Fig. 4 is a view in cross-section of the forepart of the shoe on an enlarged scale;

Fig. 5 is a plan view showing the lasted upper of the Littleway type;

Fig. 6 is a similar view showing the welt sole in position on the shoe bottom, and

Fig. 7 is a view in cross-section of the forepart of the shoe on an enlarged scale.

In producing the moccasin type shoe as shown in Figs. 1-4 of the drawings the upper is fully lasted in the usual manner forming a bottom portion or insole member 10 which is overlasted upon the last bottom and upturned walls 11 conforming accurately to the shape of the last.

12. The forepart of the vamp may be then trimmed and closed by sewing into it the usual forepart plug. These are conventional steps in the manufacture of true moccasin type shoes and in making shoes of the other types mentioned similar steps are followed except that the upper is lasted over a last having an insole which takes the place of the bottom portion 10 of the moccasin type shoe.

In carrying out the present invention a weltsole 13 is dried out or rounded to the proper size, and in this step a forepart blank 14 is dried out or partly dried out in such manner as to define a marginal welt strip 15 which extends laterally beyond the upper sufficiently to be used as the normal outsole attachment base. If the blank 14 is completely dried out it may be detachably connected and retained in place by tabs of tape joining it to the adjacent edge portions of the midsole 13 or, as herein shown, key points of integral attachment may be left intact. In any case the blank remains in place during the sole laying operation and a subsequent stitching operation. In Fig. 2 the midsole or welt sole 13 is shown as having been laid and adhesively attached to the shoe bottom. In this condition a pair of opposite and longitudinally spaced points and another pair of opposite and transversely spaced points integrally connect blank 14 directly to the midsole 13.

The last is now removed and the midsole 13 stitched to the overlasted bottom portion 10 by a line of stitching 16 which may be either of the McKay or Littleway type as desired. The line of stitching 16 may pass entirely around the margin of the shoe including the heel seat, or it may terminate at the heel breast line, and the midsole may be of integral construction or include a dutchman for its heel seat portion. The stitching operation is carried out while the blank 14 remains in place and consequently, due to the welt strip 15 being stabilized by its securement to the blank 14, the outer edge of the marginal welt strip of the midsole serves as a reliable guide. The presence of the blank prevents distortion or displacement of the welt strip 15 so that accuracy of stitching is insured without requiring any unusual skill on the part of the operator.

When the seam 16 has been completed, the blank 14 is removed as suggested in Fig. 3 and replaced by filler material which may take the form of a sponge rubber blank 17 or other light cushion material.

The shoe is completed by laying an outsole 18 upon the midsole and filler and securing it to the welt strip 15 by a stitchline 19, this being preferably a lockstitch seam concealed in a channel of the outsole as clearly shown in Fig. 4.

In producing a shoe of the Littleway type as shown in Figs. 5-7 the upper 21 is fully lasted over an insole 20 upon the last bottom. The overlasted margin of the upper is indicated by reference character 22. In this instance the overlasted margin is secured to the insole by staples and cement in the conventional manner.

In carrying out the present invention a welt sole 23 is dried out in such manner as to define a marginal welt strip 25 extending laterally sufficiently to be used as the normal outsole attachment base and detachably connected and retained in place in the sole by key points of integral attachment which are left intact. In any case the blank remains in place during the sole laying operation and the subsequent stitching operation which takes place after the upper is removed from the last. As shown in Fig. 6 the Littleway lockstitch seam 26 extends through the insole 20, the overlasted margin 22 of the upper and the welt strip 25 formed about the forepart of the welt sole.

The stitching operation is carried out while the blank 24 remains in place and consequently, due to the welt strip 25 being stabilized by its securement to the blank 24, the outer edge of the marginal welt strip 25 serves as a reliable guide for the stitching mechanism. As in the moccasin type shoe the presence of the blank 24 prevents distortion or displacement of the welt strip so that the accuracy of the stitching is insured.

When the seam 26 has been completed, the blank 24 is removed and replaced by filler material which may take the form of a sponge rubber blank 27.

The shoe is completed by laying an outsole 28 upon the midsole and filler and securing it to the welt strip 25 by cement or other suitable means.

The present application is a continuation-in-part of my application Ser. No. 460,369 filed October 5, 1954, now abandoned in favor of this application.

Having thus disclosed my invention and described in detail a preferred manner of carrying it out, I claim as new and desire to secure by Letters Patent:

1. The process of making a moccasin shoe which comprises the steps of lasting a moccasin vamp having a sole element, preliminarily attaching to the sole portion of the lasted vamp a midsole having a blank fitting within its forepart and shaped and disposed to define the inner periphery of a marginal welt strip, said blank being connected with said welt strip only at a plurality of pairs of opposed points, at least one of said pairs of points being located at positions disposed for stabilizing the toe end of said welt strip, removing the last and sewing the upper to said welt strip while the welt strip is being stabilized by its connections with said blank, disconnecting said blank from the welt strip at said points, removing the blank from the forepart and replacing it with a flexible filler, laying an outsole against said midsole, welt strip and filler and stitching said outsole to the welt strip.
2. The process of claim 1 wherein the upper is sewed to said midsole about its entire margin including the heel seat thereof as well as the welt strip of the forepart.
3. The process of claim 1 wherein said connections are provided by bonds integral with said blank and said welt strip.
4. The process of claim 1 wherein said one pair of points is located substantially along the longitudinal axis of the shoe.
5. The process of claim 1 wherein one of said pairs of points is located substantially along the ball line of the shoe.
6. The process of claim 1 wherein said bonds are of minimal dimension along the line of separation between said blank and said welt strip.
7. The process of claim 1 wherein there are but two pairs of opposed points, one pair being located substantially along the longitudinal axis of the shoe and the other pair being located substantially along the ball line of the shoe, and all the bonds being of minimal dimension along the line of separation between said blank and said welt strip.
8. The process of making a shoe which comprises the steps of preliminarily attaching to the lasted underlying portion of an upper forming a part of the shoe bottom construction a weltsole having an extension edge and a blank fitting within its forepart and shaped and disposed to define in the sole the inner periphery of a marginal welt strip extending laterally beyond the upper sufficiently to be used as the normal outsole attachment base, said blank being connected with the welt strip only at a plurality of pairs of opposed points, at least one of said pairs of points being located at positions disposed for stabilizing the toe end of said welt strip, removing the last and sewing the upper to said welt strip while the welt strip is being stabilized by its connections with said blank, disconnecting said blank from the welt strip at said points, removing the blank from the forepart and replacing it with a flexible filler, laying an outsole against said weltsole and its marginal welt strip and filler, and attaching the outsole to the welt strip.
9. The process of making a shoe which comprises the steps of preliminarily attaching to the lasted underlying portion of an upper forming a part of the shoe bottom construction a weltsole having an extension edge and a blank fitting within its forepart and shaped and disposed to define in the sole the inner periphery of a marginal welt strip extending laterally beyond the upper sufficiently to be used as the normal outsole attachment base, said blank having opposed connecting portions with the welt strip, said connecting portions between the welt strip and blank being located at points so positioned as to

stabilize the tip end of the toe portion of said welt strip, removing the last and sewing the upper to said welt strip while the welt strip is being stabilized by its connections with said blank, disconnecting said blank from the welt strip at said points, removing the blank from the forepart and replacing it with a flexible filler, laying an outsole against said weltsole and its marginal welt strip and filler, and attaching the outsole to the welt strip.

10. The process of claim 8 wherein said one pair of points is located substantially along the longitudinal axis of the shoe.

11. The process of claim 8 wherein one of said pairs of points is located substantially along the ball line of the shoe.

12. The process of claim 9 wherein said connecting portions are of minimal dimension along the line of separation between said blank and said welt strip.

13. The process of claim 8 wherein there are but two

5 pairs of opposed points, one pair being located substantially along the longitudinal axis of the shoe and the other pair being located substantially along the ball line of the shoe, and all the connecting points being of minimal dimension along the line of separation between said blank and said welt strip.

CERTIFICATE OF CORRECTION

Patent No. 2,826,770

March 18, 1958

William B. L. Freeman

It is hereby certified that error appears in the printed specification of the above numbered patent requiring correction and that the said Letters Patent should read as corrected below.

Column 1, line 17, after "lasted thereon." insert

--- While the invention has a particularly advantageous field of use in the manufacture of moccasin type shoes, it is by no means limited thereto but has a more general application to the manufacture of shoes by the Compo, McKay or Littleway welt processes. In all instances, however, the process of this invention produces shoes in which the upper is completely lasted and shaped to the last before the welt-forming element is brought into its place in the shoe bottom. ---.

Signed and sealed this 29th day of April 1958.
